OIL REFINER PACK CASING

Albert R. White, Glendale, Calif.

Application January 8, 1940, Serial No. 312,987

3 Claims. (Cl. 210—131)

My invention relates to improvements in an oil refiner pack casing, and it consists of the combinations, constructions and arrangements hereinafter described and claimed.

An object of my invention is to provide an oil refiner pack casing that is an improvement over the casing shown in my co-pending application Serial No. 234,969, filed October 14, 1938. Novel means for providing a tight oil seal between the cover and the casing proper is shown in the co-pending case. In the present device, I provide the outer surface of the casing with lugs that are received between the ends of bands that secure the casing to a support. The lugs prevent rotation of the casing within the bands when the cover is screwed into closed position or is removed from the casing body.

In my co-pending device, the oil inlet opening is placed in the cover whereas in my present form, the oil inlet is shown in the casing body rather than in the cover. The casing may be made in various sizes and I have illustrated two in the drawings. In the larger size, two oil inlets are formed in the sides of the casing and permit an oil inlet pipe to be secured to either side of the casing. The inlet not used is closed by a plug. In the smaller casing, the oil inlet is preferably disposed at the front of the casing body.

The bottoms of both the small and large casings are formed with oil sumps and I have shown two sumps in each casing. The sumps are closed by means of plugs and if desired, the oil inlet pipe may be connected to either sump.

The cover for the casing body has a plurality of projections spaced from each other for receiving a bar or other tool whereby the cover may be rotated into closed or open position. The cover has a threaded connection with the casing and a gasket is placed between the parts in the manner shown in my co-pending application Serial No. 234,969, now Patent No. 2,249,071, issued July 15, 1941.

I provide novel cooperating means between the cover and the oil refiner pack for holding the top of the pack against lateral movement. The particular construction of the oil refiner pack forms the subject matter of my co-pending application, Serial No. 312,986, filed January 8, 1940, now Patent No. 2,320,990, issued June 8, 1943. The device is simple in construction and provides an efficient oil refiner for an automobile engine or the like.

Other objects and advantages will appear in the following specification, and the novel fea-

tures of the device will be particularly pointed out in the appended claims.

My invention is illustrated in the accompanying drawing forming a part of this application, in which

Figure 1 is a front elevation of a large casing, portions being broken away to show the oil refiner pack in elevation;

Figure 2 is a bottom plan view of Figure 1;

Figure 3 is a section along the line 3—3 of Figure 1;

Figure 4 is a view similar to Figure 1, and shows a smaller casing;

Figure 5 is a top plan view of Figure 4;

Figure 6 is a sectional view through a modified form of cover and oil refiner pack; and

Figure 7 is a sectional view through another modified form of cover.

In carrying out my invention, I will first describe the large device and then the small one. I provide a casing body or receptacle A, see Figure 1, that is closed by means of a cover B. Lugs 1 are formed integrally with the outer front face of the casing and clamping bands 2 extend half way around the casing body, see Figure 2, and have their ends 3 bent outwardly to bear against the opposite sides of the lugs 1. The ends 3 of each pair are connected together by bolts 4 and have their other ends 6 connected together by bolts 5. The ends 6 of the bands are bent outwardly at right angles and the ends of each pair are in alignment with each other. The ends 6 are adapted to be attached to a supporting surface, not shown.

The casing body A has an oil outlet consisting of a central boss 7 that extends from both surfaces of the casing bottom 8. This boss receives the threaded end of an oil outlet tube 9 that projects from an oil refiner pack 10. The pack is described in detail and claimed in my co-pending case, Serial No. 312,986, filed January 8, 1940, now Patent No. 2,320,990, issued June 8, 1943. An oil outlet pipe indicated by the broken line 11 communicates with the oil outlet 7 and the pipe carries the refined oil back into a crank case 12 of an engine 13 shown diagrammatically in Figure 1.

An oil inlet opening 14 is provided on each side of the casing body A and near the top thereof. An oil inlet tube 15 may be inserted in either opening 14 and the opening not receiving the tube, is closed by means of a plug 16, see Figure 4. The tube 15 leads to the crank case of the engine and carries oil from engine to the oil refiner.

The bottom of the casing has two sumps 17 formed therein and these sumps have drain openings closed by screw plugs 18. The sumps are for the purpose of collecting foreign matter that drops off from the oil refiner pack surface. The plugs 18 may be removed from time to time to drain the sumps of sediment. If desired, the oil inlet tube 15 may be connected to either one of the sumps by removing the plug 18 from the desired sump and inserting the tube 15 in the sump opening. The inlet tube may be thus connected to the desired sump when the device is placed in a horizontal position rather than in a vertical one.

The upper portion of the casing body A is made thicker in order to form a relatively broad rim 19. The rim has concentric ribs which form corrugations in a gasket 20. The cover B has a shoulder 21 which is disposed opposite to the rim 19. The shoulder 21 has concentric grooves which are complementary to the ribs and further cause the gasket to be corrugated. The outer edge of the rim 19 is threaded at 22 and receives the threaded interior portion of the cover B.

The cover has projections 23 spaced from each other, see Figures 1 and 5, and a bar or a tool handle may be inserted between the opposed projections for rotating the cover into closed or open position. The projections 23 take the place of the hexagonal central projection shown in my co-pending application Serial No. 234,969, now Patent No. 2,249,071, issued July 15, 1941.

The smaller casing is shown in Figures 4 and 5 and parts corresponding to the larger casing will be given like reference numerals. The smaller casing A' is supported by the bands 2 and is held against rotation by the lugs 1. The casing has the outlet opening 7 and the sumps 17 which are closed by the screw plugs 18.

In place of the double oil inlet openings 14, I show a single oil inlet opening 25 which is placed at the front of the casing body A'. The oil inlet pipe 15 shown in Figure 1, communicates with the casing inlet 25 and the oil outlet pipe 11, also shown in Figure 1, communicates with the casing outlet 7. The smaller casing body A' receives the same cover B as the larger casing A. The smaller casing has the rim 19 with its concentric ridges and the gasket 20 rests on the rim. The cover B has the shoulder 21 with its complementary concentric grooves for corrugating the gasket.

The oil refiner pack 10 carries the oil outlet pipe 9 and this pipe projects beyond the top of the pack as shown at 26 in Figures 1 and 4. The portion 26 is shown wider than the lower portion of the pipe 9 because it is flattened to close the top of the pipe. The flattened pipe portion 26 is received in an annular flange 27 that extends inwardly from the cover B. The flange 27 forms a cup-shaped recess that has an inner diameter slightly greater than the width of the closed end 26. The flange prevents lateral movement of the top of the pack with respect to the casing. If the pack were only supported by the pipe connection with the boss 7, the tendency of the top of the pack to move laterally through the jarring of the automobile, would break the pipe at the boss.

It is possible to support the top end of the pipe in other ways than that shown in Figures 1 and 4. For example, in the modified form shown in Figure 6, the top of the oil outlet tube is left open as at 26a. The tube is flattened at 28 to close this end of the tube and prevent oil from pass-

ing therethrough. The flattened portion 28 has an opening 29 for receiving the key 30 by means of which the pack body is keyed to the core. In all other respects, this type of pack is the same as that shown in my co-pending application Serial No. 312,986, filed January 8, 1940 now Patent No. 2,320,990, issued June 8, 1943.

The cover B' shown in Figure 6, has a central conical shaped projection 31 for entering the open pipe end 26a. In addition, a plurality of projections 32 are spaced radially from the projection 31 and are circumferentially arranged to bear against the outer surface of the tube end 26a should the tube tend to move laterally and the central projection 31 fail to prevent this movement. The projections 32 also act as spacers between the top 10a of the pack 10 and the inner surface of the cover. The projections 32 coact with the central projection 31 to bear against the inner and outer sides of the tube simultaneously to give the top end of the tube dual support. This dual support for the tube top is necessary since the tube is under constant vibration when the oil refiner is used on an engine for heavy duty work such as operating a dirt carrying device.

Still another modified form for securing the top of the pack against lateral movement is shown in Figure 7. In this form, the central projection 31 is enclosed in an annular flange 33 corresponding to the flange 27. The open end 26a of the oil outlet tube receives the projection 31 and is held against lateral movement by the flange 33 should the projection 31 fail to hold. The projections 32 and the flange 33 are shown on an enlarged scale in Figures 6 and 7 and it should be remembered that their distance from the tube 26a is just sufficient to prevent a lateral movement of the pipe top beyond a predetermined point. In this way, the top of the pack is held against lateral movement and the outlet end of the tube or pipe 9 is freed from the strain of supporting the entire pack against such movement. The life of the pack is thereby increased. The inner surfaces of the flanges 27 and 33 may be tapered for guiding the top of the pipe into place. The tapering of the projection 32 not only guide the tube top into place, but of necessity give a dual support to the tube. When the pack and casing are disposed in a horizontal position due to less room under motor car hoods, the dual tube support gives double protection and is vital. Where the end of the pack nearest the cover is heavily weighted with oil and sludge, the dual support for this end of the tube is needed.

While I have shown only the preferred form of my invention, it should be understood that various changes or modifications may be made within the scope of the appended claims without departing from the spirit of the invention.

I claim:

1. In combination, a casing having an oil inlet and an oil outlet, a cover for the casing, an oil refiner pack having a centrally disposed oil outlet tube projecting beyond each end of the pack, the outlet end of the tube being threaded into the oil outlet so as to be held against lateral movement with respect to the casing, said cover having an integral and conical central projection for entering the other end of the tube, the base circumference of the conical projection being larger than the tube interior so that the tube top will be gripped for holding this end against lateral movement with respect to the casing, whereby both tube ends are anchored to the casing for

holding the pack in place, said tube having a flattened portion adjacent to said other end for sealing this end of the tube.

2. In a filter, a cylindrical casing open at its top and having a head at its lower end formed with a boss at its center, the boss being formed with a threaded bore, an outlet tube of perforated metal extending vertically in the casing and having an externally threaded lower end portion screwed into the threaded bore of the boss, the upper end of the tube being cylindrical and open with a flat collapsed portion adjacent to the tube top for closing and sealing the tube at the collapsed portion, a filter pack surrounding the tube with the circular open-ended top portion of the tube projecting upwardly from the filter pack, and a removable cover for the casing in threaded engagement therewith, said cover being formed with an integral depending projection for entering the open tube top for supporting the tube end against lateral displacement, said cover also being formed with an integral depending flange to form a socket for engaging with the outer surface of the top tube end to aid the projection in giving additional strength for bracing the tube against lateral movement and retain the pack in

spaced relation to the top and side walls of the casing.

3. In a filter, a cylindrical casing open at its top and having a head at its lower end formed with a boss at its center, the boss being formed with a threaded bore, an outlet tube of perforated metal extending vertically in the casing and having an externally threaded lower end portion screwed into the threaded bore of the boss, the upper end of the tube being cylindrical and open with a flat collapsed portion adjacent to the tube top for closing and sealing the tube at the collapsed portion, a filter pack surrounding the tube with the circular open-ended top portion of the tube projecting upwardly from the filter pack, a removable cover for the casing in threaded engagement therewith, said cover being formed with an integral depending projection for entering the open tube top for bracing the tube against lateral movement and retain the pack in spaced relation to the top and side walls of the casing, and a key extending transversely through the flattened tube portion and projecting into the pack for keying the pack to the tube.

ALBERT R. WHITE.
